UNITED STATES PATENT OFFICE.

HORATIO S. MOORE, OF MONONGAHELA, PENNSYLVANIA, ASSIGNOR OF ONE-HALF TO THOMAS M. EVANS, OF MCKEESPORT, PENNSYLVANIA.

HAULAGE SYSTEM.

SPECIFICATION forming part of Letters Patent No. 769,911, dated September 13, 1904.

Application filed March 24, 1904. Serial No. 199,722. (No model.)

To all whom it may concern:

Be it known that I, HORATIO S. MOORE, of Monongahela, Washington county, Pennsylvania, have invented a new and useful Haulage System, of which the following is a full, clear, and exact description, reference being had to the accompanying drawings, forming part of this specification, in which—

Figure 1 is a partial side elevation of my haulage system at the point where the clutch is automatically closed. Figs. 2 and 3 are cross-sections of the car on a larger scale, showing the clutch in open and closed positions, respectively. Fig. 4 is a view similar to Fig. 1, showing the device for opening the clutch. Fig. 5 is a cross-sectional view showing the opening device engaging the clutch member, and Figs. 6 and 7 are respectively a longitudinal section and a cross-section of my preferred form of clutch.

My invention relates to the class of rope-haulage systems for cars, and is particularly adapted for coal-mines, although it may be used in any place where a car is to be automatically engaged with a traveling rope by which the car is drawn along.

The object of the invention is to provide a simple and effective system whereby the clutch device on the car may be lowered into alignment with the rope to engage with the rope and will be normally above the level of the rope when not engaged. It is also designed to provide for automatically actuating the clutch device for engaging the rope when the car is lowered and also for disengaging and allowing the rope to drop.

In the drawings, 22 represent the rails of a track on which travels the car 3, which I have shown as arranged for receiving coal. The rope 5 extends over suitable pulleys or supports between the rails of the track in a position to be seized by the clutch or gripping device when desired. The gripping device extends transversely of the car-bottom between 45 wheels and is shown in detail in Figs. 6 and 7. It consists of a toggle device having two toggle-links 6 and 7, the link 6 being pivoted to the transverse frame 8, while the link 7 is pivoted to the link 6 and at the other end to a

sliding gripper 9, secured to a head 10, movable in guideways in the support. The links 6 and 7 may be of any desirable form, and one of them may be in the shape of a double link, if desired. One of these links and preferably the link 6 is provided with an integral 55 depending hook 11, which when the toggle is straightened extends horizontally, as shown in full lines. The grip-block 9 is preferably curved at its entrance, as shown at 12, and then reversely curved at its inner part, as 60 shown at 13. This gives a shoulder between these two curved portions, which prevents dropping out of the rope. The curved face 12 also enables the rope to open the clutch if it is partially closed at the time when it is to 65 be engaged.

Opposite the curved portion 13 of the grip-block 9 is a sliding grip-block 14, which is backed up by a strong spiral spring 15, the tension of which may be adjusted by a set-screw 16. The block 14 is so positioned that the rope will engage it and force back the spiral spring during the last part of the closing of the toggle, so that the rope is held under spring-pressure when gripped. This compensates for any inequalities in the rope and insures locking of the grip. The toggle is preferably arranged so that it is forced slightly above a straight line and near its outer lengths, thus locking it in place, and the spring serves 80 to hold the grip firmly clamped on the rope, as the movable jaw retreats slightly during the final locking movement.

In order to prevent improper action of the toggle as it is forced up, owing to the side 85 thrust of the cam thereon, I provide depending side wings 17, which inclose the links 6 in all positions. When the toggle is opened and in the position shown in dotted lines, the side thrust of the cam will be prevented from injuring or giving improper action to the clamp of these side wings or guides 17. The downward drop of the toggle is limited by a suitable stop, which in this case is formed by the inner end of the guide for the block 10. 95

In Fig. 1 I show that portion of the track where the rope is automatically clutched. In this portion of the track is a sharp depression

extending from *a* to *b*, the track thence extending on a lower level for at least a short distance until the clutch is actuated. At or near the lower end *b* of this inclined portion is located a cam 18, consisting, preferably, of a wedge-shaped piece located longitudinally between the rails and either formed of iron or faced with a steel or iron strip along its top. This incline or cam is arranged to contact with the depending hook 11 of the toggle and forces the toggle up into gripping position as the car moves along the depressed portion of the track. The lower or front portion of the cam may be rounded or twisted to fit the hook 11 in its lower position, if desired, so that the cam-surface will fit the lower face of the hook at all points in its length.

The cam is preferably pivoted at its lower end, its higher end being supported on a strong spiral spring, as shown, to allow for wearing of the wheels or for slightly-different sizes of the wheels.

By depressing the track at the point where the clutch is engaged I am enabled to bring the clutch down over the rope and into proper position to engage it before the clutch is actuated. To move the car to this portion of the track, beginning at *a* the track may be provided with a slight grade, so that the car will travel by gravity, or the car may be moved by any other suitable means. After the clutch has been automatically engaged the track may, of course, extend on any desired level, and as the car moves along it will lift the rope from its rollers or supports, the clutch traveling over them.

In Figs. 4 and 5 I show the arrangement for automatically disengaging the car from the haulage-rope. This disengaging means consists simply of an inverted cam device, which I show as consisting of an inclined angle 19, the inclination of which is forward and downward in the direction of the travel of the car. This disengaging device is preferably pivoted at its lower end, and its other end may be raised and lowered by a cam 20, actuated by a cam-lever 21. This lever serves to throw the device into operative or inoperative position, so that the car may be disengaged at this point or may remain clutched to the haulage-rope. The device 19 is arranged so that it will engage the depending hook 11 and draw downwardly upon it as the car moves forward, thus opening the toggle and disengaging the rope, which will drop down below the toggle onto its supports. The shape of the face 13 of the grip-block through the downward strain of the rope enables the rope to assist in opening the clutch after the toggle has been moved slightly.

The advantages of my invention result from lowering of the car so that the clutch will be brought in the proper position to engage the rope. This avoids any lifting of the rope into position for engagement and enables the clutch

to be normally above the rope-level, so that there will be no accidental engagement. The clutch device is simple and easily operated and gives an efficient clutching action. The spring thereon compensates for any inequalities in the rope and also enables the final locking movement of the toggle to take place. The grip is automatically actuated and also automatically unlocked, if desired.

Many variations may be made in the form and arrangement of the grip or clutch, the car, or device for locking and unlocking the clutch, &c., without departing from my invention.

I claim—

1. In a haulage system, a track having a depressed portion and a car having a gripping device arranged to be brought into alignment with the rope as the car moves down the incline; substantially as described. 80

2. In a haulage system, a track having a downward incline, a cam device at or adjacent to the incline and a car having a gripping device arranged to be brought into alignment with the rope as the car moves down the incline; substantially as described. 85

3. The combination with a driving-rope, of a car having a gripping device, comprising jaws and means for locking the jaws upon the rope, said jaws being yieldingly clamped to compensate for inequalities in the rope; substantially as described. 90

4. The combination with a driving-rope of a car having clamping-jaws, and means for locking said jaws upon the rope, at least one of the jaws having a spring-backing to compensate for irregularities in the rope; substantially as described. 100

5. In a haulage system a car having a toggle device, a jaw actuated by the toggle device, a spring-backed jaw coacting with the toggle-jaw, and means for forcing the toggle above its straight-line position to lock the grip; substantially as described. 105

6. A car having a gripping device comprising a toggle, a jaw actuated by the toggle, a depending hook on the toggle, and a disengaging device arranged to engage the hook and unlock the toggle; substantially as described. 110

7. In a haulage system, a driving-rope, a car having a gripping device, and means for raising and lowering the car relative to the rope to bring the gripping device into or out of alignment with said rope; substantially as described. 115

8. In a haulage system, a car having a gripping device, a cam device in the track arranged to automatically unlock the grip and connections for throwing the cam device into or out of operative position; substantially as described. 120

In testimony whereof I have hereunto set my hand. 125
